UNITED STATES PATENT OFFICE

MIRIAM GROSS, OF MILWAUKEE, WISCONSIN, ASSIGNOR TO MIRIAM GROSS COMPANY, OF MILWAUKEE, WISCONSIN, A CORPORATION OF WISCONSIN

DESIGN FOR A KNITTED ENSEMBLE DRESS

Application filed February 28, 1931. Serial No. 38,880. Term of patent 7 years.

To all whom it may concern:

Be it known that I, MIRIAM Gross, a citizen of the United States, residing at Milwaukee, in the county of Milwaukee and State of Wisconsin, have invented a new, original and ornamental Design for Knitted Ensemble Dress, of which the following is a specification, reference being had to the accompanying drawings, forming part thereof.

In the drawings:

dress embodying this invention showing, diagrammatically, the design incorporated in the knitting thereof.

I claim:

The ornamental design for a knitted ensemble dress as shown and described.

MIRIAM GROSS.
